UNITED STATES PATENT OFFICE.

BURNS D. LOCKWOOD, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

CAR-TRUCK.

1,212,236.

Specification of Letters Patent. Patented Jan. 16, 1917.

Application filed December 24, 1915. Serial No. 68,525.

To all whom it may concern:

Be it known that I, BURNS D. LOCKWOOD, a citizen of the United States, residing at No. 366 Lincoln avenue, Bellevue, in the county of Allegheny and State of Pennsylvania, have invented certain new and useful Improvements in Car-Trucks, of which the following is a specification.

An object of the present invention is to provide improvements in what is known to railway engineers as the "Fox" type of truck for railway rolling stock, or in trucks of similar type, and particularly to increase the strength of the truck without increasing its size or materially changing its proportions.

Railway cars have increased in capacity from, say 60,000 lbs. in 1900 to 120,000 lbs. or more, in 1915, but little attention has been given to the strengthening of the "Fox" type of truck, the same having been used practically without change in construction notwithstanding such increase in car capacity, one of the reasons therefor being that the side frames of these trucks are formed by pressing sheet metal to shape in expensive dies and an increase in the size or proportions of such trucks would render such dies useless.

An example of the "Fox" type of freight car truck is illustrated in United States Patent No. 468,146, granted to D. L. Barnes, February 2nd, 1892. An example of the "Fox" type of truck especially adapted for locomotive tenders is found in United States Patent No. 505,159, granted to S. Fox, September 19th, 1893, both of these patents illustrating trucks in which the side frames are formed of pressed steel.

Trucks of the "Fox" type are constructed with rigid side frames which at their central portions support the transoms, the side frames transmitting the load from the transoms to the car axles through the medium of U shaped pedestals formed at the ends of the rigid side frames, which pedestals receive and are supported by springs mounted on the axle journal boxes, the legs of said pedestals also forming bearings in which the journal boxes slide vertically. Sometimes the side frames of "Fox" trucks are built up of plates and commercial sections, an example of such built-up side frame being found in United States Patent No. 553,431, granted to C. T. Schoen, January 21st, 1896.

A specific object of the present invention is to so strengthen the side frame of the "Fox" type of truck as to adapt it for use in railway rolling stock of increased capacity without materially increasing the proportions of the truck.

This invention is illustrated and described in its adaptation for use as a freight car truck, but without special description it will be readily appreciated that the improvements are equally applicable to all trucks of the "Fox" or similar type when adapted for use in connection with locomotive tenders. Only so much of the "Fox" truck will be described as is necessary to illustrate this particular invention, references being had to the accompanying drawings in which like characters refer to like parts, and in which:

Figure 1 is a sectional side elevation of a "Fox" truck, Fig. 2 is a sectional plan view of the same, and Figs. 3 and 4 are vertical sections taken on lines 3-3 and 4-4 respectively of Fig. 1. Fig. 5 is a sectional side elevation of a modification of the invention, and Fig. 6 a plan view of the same, Figs. 7 and 8 being vertical sections taken on lines 7-7 and 8-8 respectively of Fig. 5.

Referring now in detail to the drawings, 1 indicates the side frame of what is known as the "Fox" type of truck, this side frame being similar in contour to the side frames illustrated in the patents hereinbefore referred to. The plate forming the side frame 1 is provided with an inwardly extending flange 2 extending along the top and end edge portions of the frame. To the inner side of the end portions of plate 1 auxiliary or reinforcing plates 3 are provided each having an inwardly extending flange 4 adapted to contact with and be secured to the inwardly extending flange 2 of the side frame 1. These auxiliary or reinforcing plates may extend if desired throughout the whole length of the side plate 1, but for the sake of illustration are shown in the drawings as only extending from the ends of the side frames to points near the cross frame members or transoms of the truck. The inwardly extending flange of the side frame 1 and also the inwardly extending flanges of the reinforcing plates 2 extend continuously from a point above the pedestal to the lower end portion of the pedestal leg, 110

and extend in the opposite direction as far as it may be considered desirable. These frame plates 1 and 2 are secured together through the medium of the flanges 2 and 4 in such a manner that there will be a space

5 intervening between them, as shown in the drawings, either or both of the plates being bent, as shown at 6 in Figs. 1 and 2, in such a manner as to bring them in contact with each other and be secured together by suitable means. The truck frame is provided with pedestal members 7 secured to the frame members in the manner shown in the drawings and provided with pedestal braces

10 or ties 8. The pedestal members 7 are provided with a portion 9 projecting therefrom in such a manner as to fill up the width of the space 5 intervening between the members 1 and 3, between which it is secured by

15 rivets or other suitable means.

20 10 indicates the transoms or cross tie members of the truck frame, which serve to tie together the frame members 1 forming the opposite sides of the truck, these transom members being braced and stiffened by the usual cross brace members 11 and the center brace member 12. 13 indicates a gusset member adapted to assist in securing together and bracing the transom members 10, the

25 side frame members 1 and the reinforcing members 3, these members being secured between the flanges 2 and 4 of the side frame and reinforcing members as illustrated in

30 Fig. 4 of the drawings.

35 In the modified form of construction, as illustrated in Figs. 5 to 8 inclusive, the flanges 15 on the upper and end portions of the side frame members and the flanges 16 on the reinforcing members are made to extend in a vertical and outward direction, and are secured together by rivets or other suitable means, the gusset member 17 in this construction being flanged in a vertical direction in a suitable manner to contact with

40 45 and be secured to the upwardly extending flanges of the side frame members and reinforcing members.

Further description of the essential parts of the "Fox" type of truck will be found in

50 either of the aforementioned patents, and hence features which are not pertinent to the present invention are not described herein.

Having thus described the invention, what I claim as new and desire to secure by Letters Patent is:

55 1. In a car truck, a side frame, a pedestal at one end thereof, a reinforcing plate spaced apart from said side frame, and means integral with said side frame and with

60 said reinforcing plate for securing them together, said means extending inwardly toward the longitudinal center line of the truck.

2. In a car truck, a side frame, a pedestal at one end thereof, a reinforcing plate spaced

apart from said side frame and flange means integral with said side frame and with said reinforcing plate for securing them together.

3. In a car truck, a side plate, a pedestal at one end thereof, a reinforcing plate extending for a portion of the length of said side plate and spaced apart therefrom, and means integral with said side and reinforcing plates for securing said plates together, said means extending inwardly toward the

75 longitudinal center line of the truck.

4. In a car truck, a side plate, a pedestal at one end thereof, a reinforcing plate extending for a portion of the length of said side plate and spaced apart therefrom, and flange means integral with said side and reinforcing plates for securing said plates together.

5. In a car truck, a side plate, a pedestal at one end thereof, a reinforcing plate spaced apart from said side plate, said side plate and reinforcing plate having inwardly extending flanges adapted to contact with and be secured to each other.

6. In a car truck, a side plate, a pedestal at one end thereof, a reinforcing plate spaced apart from said side plate, said side plate and reinforcing plate having integral inwardly extending flanges adapted to contact with and be secured to each other.

7. In a car truck, a frame plate, a reinforcing plate, spaced apart from said frame plate, said plates having contacting flanges secured together, and a pedestal member adapted to extend between and connect said plates.

8. In a car truck, a frame plate, a reinforcing plate spaced apart from said frame plate and secured together by flanges integral therewith, and a pedestal member extending between and connecting said plates.

9. In a car truck, a side frame member, a transom connected therewith, a reinforcing member having flanges adapted to be connected to said side frame member, and a gusset plate connecting said side frame, transom and reinforcing member, said side frame and reinforcing member being spaced apart.

10. In a car truck, a side frame having a flange at its top and end edges, a reinforcing plate spaced from said side frame and having a flange along its top and end edges, and means for securing said flanges together.

11. In a car truck, a side frame having a flange along its top and end edges, a reinforcing plate spaced from the web of said frame and secured to the flange thereof, and a pedestal secured between said frame and reinforcing plate.

12. In a car truck, a side frame, a reinforcing plate spaced from said side frame, said frame and plate having contacting flanges, and means for securing said flanges together.

13. In a car truck, a side frame plate, a

plate spaced away from said frame plate, flanges on both of said plates adapted to contact with each other, and means for securing said flanges together.

5 14. In a car truck, side frame plates, transoms extending between and connecting said plates, reinforcing plates spaced away from said side frame plates, flanges on said plates adapted to contact and be secured to each 10 other, and a gusset plate secured to said transoms and flanges.

15. In a car truck, a side frame having a flange along its top and end edges, a reinforcing plate spaced from the web of said 15 side frame and having a flange along its top and outer end edges secured to the flange of said side frame, the inner edge of said rein-

forcing plates being bent toward and secured to the web of said side frame.

16. In a car truck, a side frame having a flange along its top and end edges, a reinforcing plate spaced from the web of said side frame and having a flange along its top and outer end edges secured to the flange of said side frame, the inner and bottom edges 25 of said reinforcing plates being bent toward and secured to the web of said side frame.

In testimony whereof I affix my signature in presence of two witnesses.

BURNS D. LOCKWOOD.
